UNITED STATES PATENT OFFICE.

RICHARD A. REW, OF POMEROY, WASHINGTON TERRITORY.

STOVE.

SPECIFICATION forming part of Letters Patent No. 374,556, dated December 6, 1887.

Application filed November 23, 1886. Serial No. 219,701. (No model.)

To all whom it may concern:

Be it known that I, RICHARD A. REW, of Pomeroy, in the county of Garfield, Washington Territory, have invented a new and useful 5 Improvement in Stoves, of which the following is a specification.

My invention is an improvement in stoves, and has for an object to provide means for supplying air to the stove to aid combustion in 10 such manner and by such means that the said air will be taken from the lower stratum in the room, thus withdrawing the foul air from the room and at the same time preventing the discharge of sparks into the room; and it consists in the peculiar construction of the supply-pipe and the novel combination of said pipe and the stove, as will be described.

In the drawings, Figure 1 is a sectional view showing a part of a stove or range and illustrating my invention. Fig. 2 is a detail view, and Fig. 3 shows a slight modification.

The stove or range A may be mainly of any approved form or pattern, and I have not thought it necessary to show a complete stove, 25 but only so much thereof as is necessary to the illustration of my invention. In a plane below the combustion-chamber or fire-box A, I form a closed draft-space, B, the same being by preference formed below the step or hearth 30 of the stove, and having a flat top, 1, removable in the manner common to stove ash-boxes, a bottom, 2, and a front or side, 3. The hearth or top of this draft-space forms a convenient shelf to receive articles which it is desired to 35 keep warm, and such articles will be protected from gases rising from coals dropped into the draft-space, which also forms an ash-box, and the said articles may, by closing the front of the stove, be protected from the direct heat 40 from the coals, to which they would be exposed if the front of the stove, which may have doors, as usual, were open above the step or hearth.

The induction-pipe C, for supplying air to 45 the combustion-chamber, communicates at one end with such chamber in the construction shown through the medium of the draft-space, while its opposite end opens near to the floor of the room.

50 In the construction shown the draft-space B has a vertical partition, E, extending from its bottom nearly to its top, and has its bottom

formed with an opening, F, in front of such partition. The bottom is also provided with rails f to receive the flanges G, formed at the 55 upper end of the induction-pipe, and such pipe may be moved from the front into and out of attachment with the draft-space.

A latch device, H, is usually provided for securing the pipe in connection with the draft-space, as shown.

It is preferred to employ the construction as shown in Figs. 1 and 2; but manifestly the draft-pipe might open into the draft-space, as shown in Fig. 3, without departing from the 65 broad principles of my invention.

A particular advantage results from the form of the pipe, which is clearly shown in the drawings, it being bent into the form of a trap. By this form of the pipe any sparks or coals 70 which may be driven into the mouth of the pipe where it opens into the draft-space will be prevented from passing out onto the floor. This arrangement is especially desirable in stoves burning wood, for which it is particularly designed. In the use of such fuel, sparks and coals are, as is well known, frequently driven with great force from the stick or log, and there is danger of their being driven out of the draft-opening of such stove and igniting 75 the premises. Now, it will be seen that by the form of my induction-pipe any coals that may enter the upper end or mouth thereof will be checked by the trap and cannot pass out onto the floor.

By interposing the draft-space between the mouth of the induction-pipe and the combustion-chamber the chances of sparks or coals entering such pipe are reduced.

A damper, D, is provided to regulate the 90 admission of air to the combustion-chamber, the same being preferably a butterfly-damper arranged in the induction-pipe, as shown.

Now, it will be seen that by my invention I provide a simple inexpensive construction, 95 which will efficiently perform the desired office, will serve to prevent the passage of coals onto the floor, and will support the damper or means for regulating the admission of air to the combustion-chamber.

Having thus described my invention, what I claim as new, and desire to secure by Letters Patent, is—

1. The combination, with the combustion-

chamber of a stove or range, of a removable induction-pipe having its upper end communicating with the draft-space and its lower end opening near to the floor, the said pipe being formed with a trap-shaped bend, whereby air may be drawn from the lowest point practicable and sparks or coals will be prevented from discharging through said pipe, substantially as set forth.

10 2. The combination of the combustion-chamber, the draft-space opening thereto, and the removable induction-pipe opening into the draft-space and formed with a trap-shaped bend.

15 3. The combination, with the draft-space

having a vertical partition, E, and the combustion-chamber, of the removable induction-pipe opening at its upper end into the draft-space in front of partition E and formed with a trap-shaped bend, substantially as set forth. 20

4. The combination, with the draft-space of the stove or range, of the removable trap-shaped pipe extending nearly to the floor and provided with a damper, substantially as and for the purposes specified.

RICHARD A. REW.
